SHIPPING TUBE WITH INTEGRAL END CLOSURE

James C. Baxter, Minerva, and John H. French,
Beloit, Ohio

Application March 24, 1950, Serial No. 151,758

3 Claims. (Cl. 229—93)

1

This invention relates to shipping tubes and particularly to mailing tubes formed of flexible and resilient material such as paperboard.

The invention has for an object to provide a shipping tube of cylindrical or other generally round form with integral closure flaps at an end thereof that are formed to interlock and provide a strong closure for the end of the tube.

A further object of the invention is to provide a closure that comprises a pair of flaps that are integral with diametrically opposite quadrants of the tube and that have tongues and slots which provide an interlock to securely hold the flaps substantially perpendicular to the axis of the tube and in lapping relation across the end of the tube.

An additional object of the invention is to provide a closure that is formed by two superimposed pairs of interlocked flaps integral with the cylindrical body of the tube.

It is also an object of the invention to provide the ends of the tube with closure flaps that are of a width slightly less than the diameter of the tube and which are so connected to the body of the tube that they can readily be bent to tube closing position.

With the above and other objects in view, the invention may be said to comprise the shipping tube as illustrated in the accompanying drawings and hereinafter described, together with such modifications and variations thereof as will be apparent to one skilled in the art to which the invention pertains.

Reference should be had to the accompanying drawings forming a part of this specification, in which:

Figure 1 is a perspective view of a shipping tube embodying the invention;

Fig. 2 is a fragmentary transverse section through an end closure taken on the line indicated at 2—2 in Fig. 1;

Fig. 3 is a side elevation of the tube showing the closure flaps in their open positions in which they are extensions of the cylindrical body of the tube;

Fig. 4 is a fragmentary side elevation of an end of the tube showing one pair of flaps interlocked in tube closing position and the other pair of flaps extended;

Fig. 5 is an end elevation of the tube with the flaps interlocked in closed position, the underlying portions of the top flaps being shown in dotted lines; and

Fig. 6 is a plan view showing the end of the tube flattened and die cut to form the closure flaps.

2

In the accompanying drawings the invention is shown applied to a paperboard mailing tube 1 of cylindrical form which is provided with four flaps 2 at each of its ends that are integral 5 with the body of the tube, and that are formed to interlock across the ends of the tube to provide end closures. Each flap is of a size to cover the major portion of the end opening of the tube and has one longitudinal side edge 3 that is 10 parallel to the axis of the tube throughout the major portion of the length of the tube.

On the side thereof opposite the straight edge 3, each flap 2 has a lateral slot 4 provided with a flaring end 5 opening to the side edge of the flap. Each slot 4 extends substantially to the longitudinal center line of the flap and the inner portion of the slot preferably curves outwardly toward the free end of the flap to provide a hook-shaped locking tongue 6 between 20 the slot 4 and the outer end of the flap. The body portion of each flap has a straight edge 7 inwardly of the slot 4 on the side thereof opposite the edge 3 and an inset edge 8 outwardly of the slot 4, the side edge portion 8 forming the outer end of the locking tongue 6.

The portion of the flap between the straight edge 3 and the inner end of the slot 4 is continuous from the base to the outer end thereof and diametrically opposite flaps are adapted to 30 be interlocked by passing the locking tongues through the slots 4, so as to cause the continuous portion of each flap to extend through the slot 4 of the diametrically opposite flap and the locking tongue of each flap to engage the continuous portion of the other flap. When interlocked the tongue of each flap preferably underlies the body portion of the diametrically opposite flap as shown in Figs. 1 and 2 of the drawings. In order to enter the locking tongue of one flap into the slot of the other, the flaps are bent laterally 40 enough to allow the locking tongue of each flap to enter the lateral slot of the opposed flap, and after the locking tongues have passed through the slots, the flaps due to their resiliency and 45 that of the tube spring back into alignment and interlock as shown in Fig. 1.

The length of each of the flaps 2 is slightly less than the diameter of the tube but enough greater than the radius of the tube to provide 50 locking tongues of substantial width. In order to accommodate the ends of the flaps within the cylindrical wall of the tube, each flap has a rounded corner 9 at the outer end of its straight edge 3 and a rounded corner 10 at the outer edge 55 of the tongue 6.

In order to facilitate the bending of the flaps

at the ends thereof that are integrally connected to the cylindrical tube, notches 11 are provided at the base of each flap to provide a connecting portion of less width than the body of the flap and more readily bendable.

The end closure structure is preferably formed by a simple die cutting operation. The cutting is performed by a single stroke of a suitable die acting upon the end of the tube when it is flattened out and that has a cutting edge that conforms to the contour of the flaps as shown in Fig. 6 of the drawings. The die is formed with a continuous cutting edge that conforms to the margin of a straight axial slot 12 centrally of the flattened portion to form the straight edges 3 of adjacent flaps and the notches 11 at the inner ends of the edges 3, the rounded corners 9 and 10, edges 7 and 8, notches 11 and slots 4. The cutting away of folded edge portions of the flattened tube forms two diametrically opposite 15 flaps each of a width but slightly less than the arcuate width of a quadrant of the cylinder, two of said slots being diametrically opposite one another and provided with flaring outer ends, lateral slots extending circumferentially from opposite sides of said flaring slots to substantially the longitudinal center line of each flap and having flaring ends opening to the axial slots, said lateral slots providing a laterally extending locking tongue on each flap adapted to be passed through the lateral slot of a diametrically opposite flap.

The interlocking tongue and slot connection between each of the two pairs of closure flaps provides a very strong end closure since the axial thrust of articles within the tube is resisted by the interlocking flaps which are placed under tension by such thrusts. The tension imposed upon the flaps is exerted through the continuous edge portions of the flaps which extend through the slots 4 and resisted by the inner ends of the locking tongue 6 which are seated in the ends of the slots 4. While a single pair of opposed flaps forms a strong closure, it is preferred to employ two sets of superimposed interlocking flaps which form a multi-layer end closure of great strength.

It is to be understood that in accordance with the provisions of the patent statutes, variations and modifications of the specific devices herein shown and described may be made without departing from the spirit of the invention.

What we claim is:

1. A shipping tube of cylindrical form having four substantially equiangularly spaced axial slots of substantially equal length extending inwardly from an end thereof to provide four end closure flaps each of a width but slightly less than the arcuate width of a quadrant of the cylinder, two of said slots being diametrically opposite one

another and opening to slots extending circumferentially from opposite sides thereof to adjacent the longitudinal center line of each flap to provide a laterally extending locking tongue on the outer end of each flap.

2. A shipping tube of cylindrical form having four substantially equiangularly spaced axial slots of substantially equal length extending inwardly from an end thereof to provide four end closure flaps each of a width but slightly less than the arcuate width of a quadrant of the cylinder, two of said slots being diametrically opposite one another and provided with flaring outer ends, lateral slots extending circumferentially from opposite sides of said flaring slots to substantially the longitudinal center line of each flap and having flaring ends opening to the axial slots, said lateral slots providing a laterally extending locking tongue on each flap adapted to be passed through the lateral slot of a diametrically opposite flap.

3. A shipping tube of cylindrical form having four substantially equiangularly spaced axial slots of substantially equal length extending inwardly from an end thereof to provide four end closure flaps, each of said slots having a widened inner end to provide each closure flap with a connection to the tube body narrower than the body of the flap, two of said slots being narrow slots and of substantially uniform width throughout the major portion of their length and the other two of said slots being diametrically opposite and having flaring outer ends, each flap having a lateral slot opening to one of said flaring slots and providing a laterally extending locking tongue at the outer end of the flap adapted to be passed through the lateral slot of a diametrically opposite flap to lock the flaps together and across the open end of the tube.
